SYRINGE HEAD

Rodrick Koutnik, Vista, Calif., assignor to Coastal Dynamics Corporation

Filed Dec. 12, 1969, Ser. No. 20,649

Term of patent 14 years

Int. Cl. D24—03

U.S. Cl. D24—1

FIG. 1

FIG. 2

FIG. 3

FIG. 4

FIG. 5

FIG. 6

FIG. 1 is a perspective view of a syringe head showing my new design;

FIG. 2 is a side elevational view thereof;

FIG. 3 is a front elevational view thereof;

FIG. 4 is a top plan view thereof;

FIG. 5 is a bottom plan view thereof; and

FIG. 6 is a rear end elevational view thereof.

I claim:

The ornamental design for a syringe head, substantially as shown.
